UNITED STATES PATENT OFFICE.

ROBERT B. GOODYEAR, OF PHILADELPHIA, PENNSYLVANIA, ASSIGNOR OF ONE-HALF TO HUGHES & RUSSUM, OF SAME PLACE.

SHUTTLE-BOX-OPERATING MECHANISM FOR LOOMS.

SPECIFICATION forming part of Letters Patent No. 564,374, dated July 21, 1896.

Application filed March 16, 1896. Serial No. 583,407. (No model.)

To all whom it may concern:

Be it known that I, ROBERT B. GOODYEAR, a citizen of the United States, residing at Philadelphia, in the county of Philadelphia and State of Pennsylvania, have invented 5 certain new and useful Improvements in Shuttle-Box-Operating Mechanism for Looms, of which the following is a specification, reference being had to the accompanying drawings, making a part of the same.

My invention relates to improvements in rise-and-fall shuttle-box motions for power-looms, and is designed to shift and call any one of a series of four boxes at will.

15 The improvement consists in the combination and arrangement of three cog-wheels, all having interrupted teeth, two of them being driven wheels, and are connected to a double-pivoted lever. The driven wheels are put 20 into gear and motion by moving fingers controlled by a pattern mechanism, as illustrated in the accompanying drawings, in which—

Figure 1 is a view of a loom side having my improvement connected. Fig. 2 is a section 25 of the loom side, showing the mechanism for operating the moving fingers. Fig. 3 is an edge view of the lever, to which are connected the moving fingers. Fig. 4 is a face view of the cog-wheels. Fig. 5 is an edge view of 30 Fig. 4. Fig. 6 is a back view of one of the driven cog-wheels. Fig. 7 is a face view of the driver cog-wheel, showing the cogs in four series or divisions. Fig. 8 is a face view of the wiper-cam for moving the fingers when 35 operating "pick and pick."

Similar letters and numerals of reference indicate corresponding parts in the several figures.

A represents the loom side; B, the lay. At 40 the end of the lay B are arranged, in the usual manner, the shuttle-boxes 1, 2, 3, and 4. The shuttle-boxes are connected to the operating mechanism by the usual rod 5, carrying a shoe 6, which shoe rests on a roller fixed in the 45 end of lever 7. The levers 7 and 8 are double-pivoted. One pivot is on a stud fixed on the side of the loom-frame. The other pivot is on a stud in the short end of lever 8, as shown in Fig. 1.

50 The construction of that part of the mech-

anism which I claim as belonging to my improvement is as follows:

10 is a cog-wheel, in which are made ten teeth or cogs, five teeth being directly opposite the other five, as is shown by the dotted lines. 55 This wheel is a driver, and is fixed on the "cam-shaft" of the loom. The outer ends of these teeth are flanged, 23, the first and last space between the first and last tooth of each series being open. 60

9 9 are driven wheels, each having twelve cogs or teeth, six in each series, each series being directly opposite the other. The first and last tooth of each series has a lug 30. (See Figs. 4 and 5.) These lugs 30 enter the open 65 spaces at the beginning and end of each series of teeth on the wheel 10.

The wheels 9 9 are mounted on studs fixed to the loom side A. Each wheel 9 carries a stud, and by pitmen 15 and 16 the wheels 70 are connected to levers 7 and 8. (See Fig. 1.) To each of the wheels 9 is fixed or cast a flange 25. In these flanges are made notches 20, and on the back are cast lugs 21 and 22. It will be noticed that lug 21 is farther from the center 75 than lug 22.

14 14 are spring-brakes, each having at its lower end a V-shaped lug. These lugs engage in the V-notches 20 in the flanges 25 25.

11 is a lever hung on a stud fixed to the 80 loom side. This lever 11 carries on a stud 26 (see Fig. 3) fingers 12 and 13. These fingers 12 and 13 are by cords or wires 27 and 28 connected to the usual pattern-chain for controlling the movements of the shuttle-boxes. On 85 the lower end of lever 11 is pivoted a trigger 17. To the lever 11 is fixed a stop-lug 19. To the trigger 17 is attached a cord or wire 29, by which the trigger is connected in a well-known manner to the weft stop-motion. 90

18 is a wiper-cam fixed on the cam-shaft.

The operation of my improved shuttle-box motion is as follows: Motion is given by the cam-shaft that carries the wheel 10 and cam 18. The movement is in direction indicated 95 by the arrows, one revolution for each two picks of weft. The wiper-cam 18 and lever 11 give a to-and-fro movement to the fingers 12 and 13, which fingers, being controlled by the pattern-chain, raise or drop them so as to 100

cause them to strike in their movement the lugs 21 or 22 on wheels 9 9. The movements of the fingers and driver-wheel 10 are so timed that the push of the fingers will move the 5 wheels 9 9, so that the first tooth of a series on wheel 9 will enter the open space of the flange 23, beginning with the series of teeth on wheel 10. This flange 23 prevents the wheels 10 gearing except in the first space of each series. In the position of the shuttle-box as 15 shown in Fig. 1 the top box 1 is in use. If finger 12 now moves the wheel 9 on the right hand, it will be revolved one-half of one revolution. The stud and pitman 24 will be moved to the bottom of wheel 9. The pitman 16, being connected to lever 7, will raise the box one shelf and shuttle 2 will be used. After two picks the finger 13 may be caused 20 to strike a lug on wheel 9 to the left hand. This will cause that wheel to make one-half of one revolution, and its pitman 15, being connected to lever 8, will raise the box to shelf 4 and shuttle 4 will be used. If after two 25 picks fingers 12 and 13 both act at the same time, both wheels 9 9 will be moved, giving a full drop, and put the boxes in position, as shown in Fig. 1. Box 3 may be called, if box 1 is in position, by solely operating finger 13, wheel 9 on the left, and lever 8. This will 30 skip box 2 and bring box 3 into position. If box 2 is in position and box 3 is wanted, both pinions 9 9 are moved, lever 8 raises two and lever 7 drops one, and the box is only raised one shelf. Thus it is required to discount one 35 shelf in order to reach the one desired. The wheel 9 on the right moves one box. The wheel 9 on the left moves two boxes. Both wheels

moving at same time move three boxes, and it is plain and clear to one familiar to operating shuttle-boxes in looms that with my 40 improvements I can command any one of a series of four boxes at will, and by the modifications in wiper-cam 18 (shown in Fig. 8) I can operate pick and pick, using a four-shuttle box at each end of the loom-lay, calling 45 any one of the series of four at will.

When the loom is turned backward, the trigger 17 tilts up, and the wiper-cam 18 does not operate the lever 11, fingers 12 and 13, and so long as the loom is turned backward 50 the shuttle-box will not be moved.

Fig. 7 shows a driving-wheel divided into four divisions. Two divisions are only in use at same time. If a tooth gets broken out of one division, the wheel may be shifted on the 55 cam-shaft, bring the other opposite two divisions into use, and save the cost of a new wheel.

Having as above fully described my invention, what I claim as new, and desire to secure 60 by Letters Patent, is—

In a rise-and-fall shuttle-box mechanism for looms, the combination consisting of three cog-wheels having interrupted teeth, one a driver and two driven wheels; a wiper-cam; 65 two fingers actuated by said cam, and controlled by a pattern mechanism; a divided and double-pivoted lever connected to and operated by the driven wheels; all substantially as shown and described.

ROBERT B. GOODYEAR.
